US0D1109186S

(12) **United States Design Patent** (10) Patent No.: **US D1,109,186 S**
(45) Date of Patent: ** *Jan. 13, 2026

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Rhythm Agarwal**, Bethlehem, PA (US);
Benjamin F. Bard, Zionsville, PA (US); **Erica L. Clymer**, Northampton, PA (US); **Shenchi Tian**, Easton, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/954,884**

(22) Filed: **Jul. 30, 2024**

Related U.S. Application Data

(63) Continuation of application No. 29/801,031, filed on Jul. 26, 2021, now Pat. No. Des. 1,038,976, which is a continuation of application No. 29/697,909, filed on Jul. 12, 2019, now Pat. No. Des. 928,816, which is a continuation of application No. 29/612,918, filed on Aug. 4, 2017, now Pat. No. Des. 854,036.

CLAIM

The ornamental design for a display screen or portion thereof with graphical user interface as shown and described.

DESCRIPTION

The sole FIGURE shows a display screen or portion thereof with graphical user interface showing our new design. The peripheral dashed broken lines illustrate a display screen or portion thereof, and form no part of the claimed design.

The text illustrated in dashed broken lines form no part of the claimed design.

The horizontal dashed broken line and the faded portion below the horizontal dashed broken line form no part of the claimed design.

Shading represents tonal contrast.
